(57) **CLAIM**

The ornamental design for a game console shell, as shown and described.

DESCRIPTION

FIG. 1 is front view of a game console shell, comprising a left and right side, showing my new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a front, right and top perspective view thereof;

FIG. 8 is a rear, left and bottom perspective view thereof;

FIG. 9 is a front view of left component part of FIG. 1, shown separately for complete disclosure;

FIG. 10 is a rear view thereof;

FIG. 11 is a left view thereof;

FIG. 12 is a right view thereof;

FIG. 13 is a top view thereof;

FIG. 14 is a bottom view thereof;

FIG. 15 is a front, right and top perspective view of the left component of FIG. 1, shown separately for complete disclosure;

FIG. 16 is a rear, left and bottom perspective view thereof, showing the inner side;

FIG. 17 is a front view of right component part of FIG. 1, shown separately for complete disclosure;

FIG. 18 is a rear view thereof;

FIG. 19 is a left view thereof, showing the inner side;

FIG. 20 is a right view thereof;

FIG. 21 is a top view thereof;

FIG. 22 is a bottom view thereof;

FIG. 23 is a front, right and top perspective view thereof; and,

FIG. 24 is a rear, left and bottom perspective view thereof, showing the inner side.
